RIFLE

Nathan H. Price, Birmingham, Ala., assignor of
one-half to Mrs. Alexander Schoettlin, Bir-
mingham, Ala.

Application November 17, 1936, Serial No. 111,303

3 Claims. (Cl. 124—13)

This invention relates to air rifles and has for the primary object the provision of a device of this character which will provide a maximum amount of safety to the person operating the rifle and the charging of the rifle with air pressure may be easily and quickly accomplished without danger to the operator and which will automatically load the rifle from a magazine conveniently located on the rifle and which provides accommodation for a maximum number of shots.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating an air rifle constructed in accordance with my invention.

Figure 2 is a fragmentary vertical sectional view showing the trigger mechanism and the safety device therefor and the means for charging the rifle with air pressure.

Figure 3 is a fragmentary vertical sectional view showing the parts of the rifle positioned in the act of charging the rifle with air pressure and for loading the rifle with a shot from the magazine.

Figure 4 is a fragmentary sectional view showing the trigger mechanism in firing position.

Figure 5 is a perspective view illustrating the trigger.

Figure 6 is a perspective view illustrating a valve plate.

Figure 7 is a plan view illustrating the safety for the trigger.

Figure 8 is a perspective view illustrating the member for actuating the valve plate.

Figure 9 is a transverse sectional view taken on the line 9—9 of Figure 1.

Figure 10 is a fragmentary vertical sectional view illustrating the means for permitting the loading of the magazine with shots.

Referring in detail to the drawings, the numeral 1 indicates the stock of the rifle, 2 the breech block and 3 the barrel having a bore 4 and equipped with the usual sights. The block 2 is pivoted to the stock 1, as shown at 5, and is provided with an air chamber 6, an air passage 7 including angularly related runs 9 and 10 with the run 9 at one end opening outwardly through a face of the block and slightly enlarged at said end to form a shot seat 11. The run 9 commu-

nicates with the air chamber 6 and has therein a valve 12 of the self-seating type and including a ball 13. Secured to the block is a pump cylinder 14 movable into and out of a space 15 provided in the rifle. The cylinder 14 is connected to the air chamber 6 by a passage 16 and operating in said cylinder is a piston 17, the stem of which is indicated by the character 18 and is pivoted to an operating lever 19 which also forms a trigger guard and is pivoted to the rifle, as shown at 20. The lever 19 when positioned to act as a trigger guard positions the cylinder 14 in the space 15 of the rifle and also moves the piston 17 on its compression stroke for charging the air chamber 6 with air pressure. The rifle has a chamber 21 for the accommodation of the block 2 and the stock has a slot 22 which communicates with the chamber 21 and has located therein a keeper 23 and also a safety element 24. Pivoted to the block 2 is a trigger 25 to which the safety element 24 is pivoted. Pivoted on the block is a valve actuating plate 26 engageable with the ball 13 of the valve 12 and also with the pivoted end of the trigger 25. The trigger is influenced into a non-firing position by a spring 27 and pivoted on the block 2 is a finger piece 28 for urging the plate 26 into engagement with the ball 13 of the valve.

Secured to the barrel 3 is a magazine 29 arranged at the forward end thereof with a suitable closure 30 whereby shot may be placed conveniently in the magazine. The other end of the magazine is normally closed by the block 2. However, when said block is swung on its pivot during the suction stroke of the piston 17 the air passage 8 moves into communication with the magazine 29 and the valve 12 is opened so that a shot from the magazine will be drawn into the seat 11. The valve is opened by the trigger 25 being held by the safety 24 engaging the keeper 23. During the movement of the piston 17 on its compression stroke the swinging of the block on its pivot to its initial position causes the shot in the seat 11 to travel to the receiving end of the bore of the barrel. During this last-named movement of the block the valve is closed by actuation of the finger piece 28 and the safety 24 moving away from its keeper also during said movement of the block the run 9 having the shot in the seat thereof moves into communication with the bore of the barrel. The rifle is then charged with air pressure and loaded by having the shot in the receiving end of the barrel. The trigger when pulled will unseat the valve permitting the air pressure in the air chamber to pass therefrom

and drive the shot through the bore of the rifle with a maximum amount of force.

Having described the invention, I claim:

1. A rifle including a stock and a barrel having a bore, a breech block pivoted to the stock and having an air chamber and a passage communicating with the latter and opening outwardly through one face of the block and capable of moving into and out of registration with the barrel, a valve for controlling said air passage, a magazine carried by the barrel containing shot said block adapted to be moved to a position to register said passage with said magazine whereby to receive a shot from said magazine, and moved 10 to another position to register said passage with the bore of the barrel whereby said shot is adapted to be discharged through said barrel, a cylinder secured to the block and movable therewith, a piston operating in said cylinder, a hand lever for operating the piston and acting as a trigger guard, and for reciprocating the piston and imparting pivotal movement to the block, and a trigger for operating the valve.
2. A rifle including a stock and a barrel having a bore, a breech block pivoted to the stock and having an air chamber and a passage communicating with the latter and opening outwardly through one face of the block and capable of moving into and out of registration with the barrel, a valve for controlling said air passage, a magazine carried by the barrel containing shot said block adapted to be moved to a position to register said passage with said magazine whereby to receive a shot from said magazine, and moved 20 to another position to register said passage with the bore of the barrel whereby said shot is adapted to be discharged through said barrel, a cylinder secured to the block and movable therewith, a piston operating in said cylinder, a hand lever for operating the piston and acting as a trigger guard, and for reciprocating the piston and imparting pivotal movement to the block, and a trigger for operating the valve.

to another position to register said passage with the bore of the barrel whereby said shot is adapted to be discharged through said barrel, a cylinder secured to the block and movable therewith, a piston operating in said cylinder, a hand lever for operating the piston and acting as a trigger guard, and for reciprocating the piston and imparting pivotal movement to the block, and a trigger for operating the valve, and a safety connected with the trigger. 10

3. A rifle including a stock and a barrel having a bore, a breech block pivoted to the stock and having an air chamber and a passage communicating with the latter and opening outwardly through one face of the block and capable of moving into and out of registration with the barrel, a valve for controlling said air passage, a magazine carried by the barrel containing shot said block adapted to be moved to a position to register said passage with said magazine whereby 15 to receive a shot from said magazine, and moved to another position to register said passage with the bore of the barrel whereby said shot is adapted to be discharged through said barrel, a cylinder secured to the block and movable therewith, a piston operating in said cylinder, a hand lever for operating the piston and acting as a trigger guard, and for reciprocating the piston and imparting pivotal movement to the block, and a trigger for operating the valve, and a safety connected with 20 the trigger, and a keeper carried by the stock to be engaged and disengaged by the safety. 25
